UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

1,415,935.

Specification of Letters Patent. Patented May 16, 1922.

Application filed March 1, 1919. Serial No. 280,033.

To all whom it may concern:

Be it known that I, FRED N. LA CHAPELLE, a citizen of the United States, residing at Beverly, in the county of Essex and State 5 of Massachusetts, have invented certain Improvements in Fastening-Inserting Machines, of which the following description, in connection with the accompanying drawings, is a specification, like reference characters on the drawings indicating like parts 10 in the several figures.

This invention relates to fastening inserting machines and particularly to machines designed to shape the work and to apply a 15 fastening to secure the work in its shaped condition. While the invention may have various uses and applications, it has been applied with advantageous results to the production of shoe insoles and particularly to 20 the production of an insole which constitutes the subject-matter of a co-pending application Serial No. 256,494, filed by me October 2, 1918.

The insole referred to is formed by first 25 channeling an insole blank having a rounded, somewhat blunt end from which a V-shaped portion may be cut to form a sharply pointed toe, and turning up the lip or combined lip and flap, produced by the channeling operation, to form the sewing rib. Thereafter, the central portion of the end 30 of the toe is cut out, preferable by a V-shaped cut, and finally the sides of the cut are closed together, thus abutting the ends 35 of the rib and producing an insole with a sharply pointed toe in which the rib at all points is correctly disposed relatively to the sole edge.

It is an object of the present invention to 40 provide means which is adapted without sacrifice of other utility for shaping the notched toe of an insole, either by pressing or molding the toe into its final pointed form, and for applying a fastening to secure the toe 45 permanently in its shaped condition.

In a preferred form of the invention the means for shaping the work will be mounted between the work support and the fastening inserting mechanism and a notable 50 feature of the construction is found in the arrangement by which relative movement of the work support and the inserting mecha-

nism preliminary to the insertion of a fastening controls the operation of the work shaping means.

Other features of importance relate to the construction and arrangement of the shaping members by which they self-adjustingly accommodate themselves to the work and provide for the access of the inserting mechanism to the work while in the shaping members.

Along with the shaping of the end portion of the toe, it is desirable to compress or mold or otherwise give a more permanent 65 set to the rib which is formed by the channeling and turning-up operations. Accordingly, important features of the shaping means for the insole are found in means for engaging the rib around the toe portion of 70 the insole to compress the rib and to mold it if the leather be in temper. If a piece of fabric carrying cement or other adhesive be inserted to provide reinforcement for the rib, the fabric and rib will be molded together. 75

Preferably, the invention in its illustrative embodiment will comprise a fastening inserting mechanism so constructed and arranged as to clamp the work securely during 80 the insertion of fastenings and to insure that the fastenings will be properly set.

Other objects and features of construction will be apparent from the following detailed description and will be pointed out in the 85 claims.

In the drawings,—

Figure 1 is a plan view of the forward end of an insole showing the same after the channeling operation and with the lip and 90 flap turned up to make a rib;

Fig. 2 is a similar view with a V-shaped notch cut out of the forward end of the insole;

Fig. 3 is also a plan view of the same insole with the sides of the notch brought together and secured by a fastening; 95

Fig. 4 is a similar view to that of Fig. 3 showing a reinforce for the toe portion of the insole;

Fig. 5 is a front view of a machine for shaping an insole and for securing the parts in shaped condition;

Fig. 6 is a view in side elevation of the

lower part of the machine showing the structure of the work shaping members;

Fig. 7 is a plan view from above of the work shaping mechanism;

Fig. 8 is a perspective view of one of the work shaping members removed from the machine and turned bottom side up;

Fig. 9 is a perspective view of the other work shaping member; and

Fig. 10 is a view of the entire machine in side elevation.

In the drawings one embodiment of the invention is shown to comprise a fastening inserting machine which is preferably of the type disclosed in the patent to Borden, No. 1,016,930, granted February 13, 1912, the said fastening inserting mechanism comprising the usual wire feed device 12, fastening forming and driving devices including the fastening guiding nozzle 14, and means 16 for varying the size and shape of the fastening. For a complete description of the fastening inserting mechanism reference should be had to the said patent to Borden.

In the illustrative construction the work shaping means is shown to comprise a work support 18 mounted at the upper end of the slideable post 20 which is guided for movement in the bearings 22 of the frame 24. Carried by the frame 24 is a bracket 26 having at its forward end bearings 28 in which are slidably mounted posts 30 joined at their upper ends by a cross bar 32. Each post carries a collar 34 (Fig. 6) adjustably mounted thereon and held against the upper end of its respective bearing 28 preferably by means of a spring 36 which surrounds the lower end of the post and is engaged between the lower surface of bearing 28 and a member 38 adjustable on the post and held in adjusted position by a lock nut 40. Carried by the cross bar 32, in the illustrative machine, is a shaping member 42, means being provided in the form of set screws 44 and 46 (Figs. 7 and 9) for adjusting said shaping member toward and from a co-operating shaping member 48. In the construction shown, this latter member is pivotally mounted in a slide 50 which is arranged for reciprocation in guideways on the under surface of the table or work support 18. Referring especially to Fig. 7, it will be observed that the slide 50 is provided with two bars 52 which extend forwardly into the guideways in the table, each bar carrying a pin 54 (Fig. 6) to which is attached on each side the forward end of a spring 56 having its rear end attached to a pin 58 secured to the under surface of the table. These springs operate to hold the slide 50 yieldingly in its rearward position of rest. In order that the shaping member 48 may not be displaced laterally from operative position and yet may

have sufficient movement to permit it to be self-adjusting with respect to the work, the said member, in the illustrative construction, carries on its lower surface a pin 49 which slides along a slot 51 (Fig. 7) in the upper surface of the table or work support 18. Means are provided for moving the shaping member 48 toward its co-operating shaping member 42, the said means, in the illustrated machine, comprising a cam member 60 adjustably mounted on the upper rear end of the bracket 26 and fixed in place on said bracket by means comprising preferably a set screw 62 engaged in a slot in said member 60. The forward end of the cam member 60 is provided with a cam surface 64 normally in contact with a cam surface 66 on the rear end of the slide 50. When the table 18 which carries the slide 50, is moved upwardly, the said slide is forced forwardly by the co-operation of the cam surfaces 64, 66. Above the cam surface 66 is another cam surface 67 on member 60 which co-operates also with the cam surface on the slide 50 for purposes which will be hereinafter described. At the end of a shaping operation the table 18 moves downwardly and as this movement progresses, the springs 56 operate to return the slide 50 to its rear-most position and maintain the cam surfaces 64 and 66 constantly in contact. While, in the illustrative machine, one of the shaping members is shown stationary and the other movable with respect thereto to perform the shaping operation, it is to be understood that the scope of this invention is such as to cover an arrangement in which both members are made movable to co-operate with each other in shaping operations or an arrangement reversed from that shown by making stationary the shaping member now shown movable and causing the co-operating shaping member to move with respect thereto. In the construction disclosed, the shaping member 48 is shown provided with a forked, substantially V-shaped forward portion designed to engage spaced portions of the toe of an insole to shape the same by a pressing or a pressing and molding action, the V-shaped portion of the shaping member having preferably overhanging portions 68 to engage over the upper surfaces 70 of the edge of the insole, the vertical surfaces 72 on the shaping member being designed to engage the outer side of the upstanding rib 74 of the insole while the vertical surfaces 76 on the V-shaped portion of the presser member engage the vertical edge 78 of the insole tip to press upon and close tightly together the forked portions 79 of the insole and thus shape the forepart or tip of the insole. At the apex of the V-shaped portion of the presser

member 48 is an opening 80 designed to receive the nozzle 14 of the fastening inserting mechanism, thus permitting insertion of a fastening like that shown at 82 5 while the work is held clamped by the shaping members.

The member 42 is constructed to fit into the toe portion of the insole inside of the upstanding ribs and is arranged to press the 10 insole upon the work support to prevent buckling of the insole while it is being shaped by the co-operating shaping member 48 and has the further function of shaping the upstanding ribs in conjunction with the 15 flanges 68 on the member 48. In some cases the insoles are presented to the machine while in temper in which case there is a certain amount of molding in conjunction with the pressing which moves the forked 20 portions of the insole into abutting relation and compresses the upstanding ribs. In other cases it is desirable to insert a piece of reinforcing fabric carrying cement or other adhesive which is rendered 25 tacky on the application of heat. In accordance with this feature of the invention the member 42 will be provided with a socket 84 (Fig. 9) for the reception of a heating unit 86 designed to form part of 30 an electrical circuit. With this arrangement the member 42 will not only press the reinforcing fabric 88 (Fig. 4) into the toe portion of the insole, but will cause it to adhere firmly and be molded to the shape of the insole 35 with flange portions firmly adhering to the inner surfaces of the upstanding ribs.

Mounted in the head 90 of the fastening inserting mechanism is the driving shaft 92 having thereon the fast and loose pulleys 94 40 and 96 which are normally held in separated relation but are adapted to be placed in operative engagement by the wedge 98 connected by the rod 100 to the starting and stopping treadle 102 pivoted to the base portion 45 of the column 104 upon a pin or rod 106.

The lower portion of the work supporting post 20 extends below the lower bearing 22 and contacts with treadle controlled means whereby the work supporting post may be 50 manually raised. In the present instance this means comprises a lever 108 pivoted at 110 to a lug 112 extending from the bracket 24, the rear end portion of said lever being pivotally connected at 114 to a treadle rod 55 116 connected at 118 to a treadle 120 the fulcrum of which is preferably established on the pin or rod 106. The free end portion of the lever 108 is provided with an adjustable device upon which the lower end of the 60 work supporting post 20 rests. In the present instance this device comprises a pin 122 which may be adjustably secured to vary the lowermost position of the work supporting post 20. Preferably the post 20 is rendered 65 extensible in length by means of a turn buc-

kle construction 124 so that the work supporting table 18 may be raised without affecting the operative connections of the work supporting post with the automatic power means for operating the same. 70

In the use of the construction thus far described, it will be apparent that upon depression of the treadle 120 the work supporting post will be raised manually toward the fastening inserting mechanism, quickly 75 bringing the insole on the work supporting table into contact with the member 42 so that the work is clamped yieldingly on the table as the member 42 is carried upwardly against the action of the springs 36. At the 80 instant that the work supporting table 18 is started upwardly, the shaping member 48 is moved forwardly by reason of the co-operation between the cam surfaces 64 and 66 located respectively on the stationary cam 85 member 60 and on the carrying slide 50 (Fig. 6), so that the shaping member 48 commences at once to shape the work which has been placed on the table with the portion 90 to be shaped positioned in the bifurcated portion of the shaping member. Very shortly after the initiation of the upward movement of the work support the member 42 engages the work to co-operate with the member 48 in shaping the insole and in compressing the upstanding ribs. Since the member 48 is pivoted for slight lateral swinging movement, there is automatic adjustment of said member with respect to the member 42 as the two members come into 100 engagement with opposite sides of the upstanding ribs. Toward the end of the upward movement of the work supporting table 18, the cam surface 66 on the slide 50 leaves the cam surface 64 and enters into 105 contact with the cam surface 67 of cam member 60, thus maintaining the shaping members in clamped relation, and it is at this time that the power means for lifting the work supporting table is thrown into operation 110 through the depression of the treadle 102, the result being that the shaping members are clamped more firmly than before through the operation of said cam surface 67 just at the time that the fastening is being 115 inserted. The operation of the shaping members throughout is controlled from the work support. 120

In the illustrated construction the power means for operating the work support comprises wedge means yieldingly actuated from the means for operating the fastening inserting mechanism. As shown, the bracket 24 is provided with guideways 126, preferably one on each side of the bracket 24, in 125 each of which is mounted for reciprocating movement a wedge 128. Each of the guideways 126 may be formed by separate upper and lower flanges 130 which thus provide a passage between them for a pin 132 secured 130

to each wedge 128. Connected to each pin 132 is a rocker arm 134 secured to a rock shaft 136 mounted in suitable bearings which may be conveniently formed in the bracket 24, sufficient play or lost motion being provided between the pins 132 and the connections to permit rectilinear movement of the wedges without binding of the parts. The rock shaft 134 has secured thereto an arm 138 which may be yieldingly connected to suitable means actuated from the driving shaft 92 to impart to said arm 138 and through it and associated elements, as described, to the wedges 128, the desired movements, as will presently appear.

Secured to the main driving shaft 92 is a cam 140 having a cam path engaged by a pin or roller mounted on the arm 142 which is mounted on a rock shaft in the machine head in a bearing 144, another arm 146 of the rock shaft being connected by a rod 148 with the arm 138 so as yieldingly to actuate said arm 138. The connection between the rod 148 and the arm 138 comprises a construction in which the rod 148 passes loosely through an opening in a bearing at the outer end of the arm 138, a spring 150 being interposed between said bearing and a collar 152 adjustably secured to the rod 148, the construction being such that as the cam 140 is rotated by the main driving shaft 92 the rod 148 will be reciprocated to impart to the wedges 128 reciprocating movement in their respective guides, provided such movement of the wedges is not effectively obstructed. Should the wedges meet an effective obstruction sufficient to prevent such movement, the rod 148 will still be reciprocated but instead of moving the arm 134, on the downward movement of the rod the spring 150 will yield and simply be compressed, thus permitting the wedges to remain quiescent. By this construction it is insured that the work support will be fully raised to work clamping position and held there as the fastening inserting mechanism is operated, provided its movement toward such position has been manually started or initiated. This result is secured by providing the work supporting post with projections which, when the work support is in lowered position, will be too low to be engaged by the inclined surfaces of the wedges and consequently offer an effective obstruction to wedge movement under the action of the automatic operating means described. In accordance with the construction shown the work supporting post 20 is provided at the sides thereof in front of the wedges 128 with pins 154 preferably carrying rollers 156 for engaging the wedges 128 as the latter are moved forward by the automatic means described. When the work support is in lowered position, as for instance, when the treadle 120 is not depressed by the operative, the axes of the pins

and rollers are slightly below the front edges of the wedge inclines and if at such times the starting and stopping treadle 102 be depressed to start the machine, the actuating means for the wedges will be operated but the rollers and pins on the work support will prevent wedge movement and the work support will remain in lowered position. Should the operative have manually lifted the work support, then the axes of the pins and rollers will have been raised sufficiently to permit the wedges to engage beneath them and thus lift the work support to full work clamping position and lock it for the insertion of fastenings. For a complete description of the automatic means for operating the work support, reference should be had to United States Patent No. 1,291,754, granted January 21, 1919, to Matthias Brock for improvements in work support controlling and operating mechanisms, which discloses and claims said automatic mechanism.

Among the advantages of the manually controlled and automatically controlled work support herein described are those which relate to the control of the work support during the shaping operation. The operative through manual control of the work support has control of the shaping members at the beginning of their co-operating shaping action upon the work and can inspect the work and retain control of the shaping members practically up to the time of the insertion of the fastening into the work. By the operation of the automatic means for operating the work support the shaping members are power operated at the termination of the shaping operation to give a greater shaping effect than could readily be obtained by means operated solely by footpower and to clamp the work firmly in shaped condition during the fastening setting operation. Furthermore, power operation of the work support through the wedge means described insures perfect setting of the fastening.

Having thus described my invention, what I claim as new and desire to secure by Letters Patent of the United States is:—

1. In a machine of the class described, a work support, fastening inserting mechanism, and work shaping means mounted between the work support and said mechanism and having portions controlled by said work support and movable toward each other in a pressing operation to shape the work prior to the insertion of the fastening.

2. In a machine of the class described, fastening inserting mechanism, a work support, and work shaping means, comprising members co-operating independently of the work support for shaping the work, controlled by the movement of the work support in presenting the work to the inserting mechanism.

3. In a machine of the class described,

fastening inserting mechanism and a work support relatively movable to cause insertion of fastenings in the work on the support, and work shaping means comprising 5 members having complementary work shaping portions and operated by the relative movement of the work support and inserting mechanism.

4. In a machine of the class described, 10 fastening inserting mechanism and a work support relatively movable towards and from each other in an inserting operation, work shaping means for shaping the work prior to the insertion of fastenings, and a stationary cam for controlling the operation of 15 the shaping means, the construction and arrangement being such that said cam becomes operative upon the relative approaching movement of the work support and the 20 inserting mechanism in a fastening inserting operation.

5. In a machine of the class described, fastening inserting mechanism, a work support, and shaping means for the work comprising 25 members arranged to engage opposite sides of the work to shape the same and mounted between the work support and the inserting mechanism and movable with the work support to present the work in 30 shaped condition to the inserting mechanism.

6. In a machine of the class described, fastening inserting mechanism and a work support relatively movable to insert fastenings 35 in the work on the support, and relatively movable shaping members mounted above the work support for movement relatively to each other in a plane parallel with the work supporting surface of the work support 40 during the relative movement of the work support and the inserting mechanism.

7. In a machine of the class described, fastening inserting mechanism, a work support having a flat work supporting surface, shaping 45 means for the work between the work support and the inserting mechanism, means for operating the shaping means to shape the work while the latter is held firmly clamped on the supporting surface, and 50 means for causing the operation of the inserting mechanism on the work while it is held by the shaping means.

8. In a machine of the class described, a work support, a shaping member carried by 55 the work support and movable with the work support and also independently thereof during the shaping operation, a shaping member carried by the frame of the machine, and means for causing co-operation of the shaping members upon movement of the work support.

9. In a machine of the class described, shaping means for shaping the work comprising 60 a shaping member mounted on the frame of the machine, a work support, a

shaping member mounted for movement on the work support to co-operate with the first-mentioned shaping member, and manually operable means for causing co-operation of the shaping members and of the work support to shape the work and to hold it in shaped condition. 70

10. In a machine of the class described, a work support, shaping members for operating on the work, manually operable means 75 for causing co-operation of the shaping members, and power operated means for completing the shaping operation and for holding the work in shaped condition for subsequent operation thereon. 80

11. In a machine of the class described, a work support, co-operating shaping members mounted above the work support, the said shaping members being so arranged as to adjust themselves automatically to the work 85 upon movement of the work support toward fastening inserting position, and means for inserting a fastening into the work after the shaping operation.

12. In a machine of the class described, a work support, fastening inserting mechanism, work shaping means mounted between the work support and the inserting mechanism, manually operable means for causing the co-operation of the shaping members, 95 and power means for causing the completion of the shaping operation and the operation of the inserting mechanism. 90

13. In a machine of the class described, shaping means for the work comprising 100 shaping members mounted for relative movement with respect to each other, one of the shaping members being mounted on the frame of the machine and the other shaping member being pivotally and slidably mounted on the work support to co-operate with and to adjust itself automatically to the first-mentioned shaping member, and stationary means operable during the movement of the work support for causing co-operation of said shaping members. 105

14. In a machine of the class described, a work support, a shaping member mounted above the work support, a co-operating shaping member mounted pivotally on the work 110 support, means for causing the pivotally mounted shaping member to approach and recede from the other shaping member, and means for inserting a fastening while the work is held in the shaping members. 115

15. In a machine of the class described, shaping members for acting upon the notched toe portion of an insole to shape the same comprising a shaping member having a vertical surface to engage the vertical edge 125 of the toe portion of the insole in order to move the separated toe portions toward each other and hold them in abutting relation and having another surface for engaging the upstanding rib on the insole to compress the 130

same in co-operation with the other shaping member.

16. In a machine of the class described, shaping means for the work comprising a 5 V-shaped member and a co-operating shaping member having a correspondingly V-shaped notch, the notched member having surfaces to engage respectively with the vertical edges of the toe portion of the insole 10 and the vertically arranged ribs on said insole to shape the same in co-operation with the first-mentioned shaping member.

17. In a machine of the class described, fastening inserting mechanism, a work support, 15 a shaping member for the work mounted on the frame of the machine, a second shaping member mounted on the work support, and means for moving the work support and the last-mentioned shaping member 20 toward the first-mentioned shaping member along angularly related paths to cause a shaping operation upon the work and subsequently the insertion of a fastening.

18. In a machine of the class described, 25 fastening inserting mechanism, a work support, a shaping member, means for mounting the shaping member yieldingly in the frame of the machine, a co-operating shaping member mounted on the work support, and means 30 for causing the co-operation of the shaping members to shape the work and for moving both shaping members while in their work clamping position into operative relation with the inserting mechanism.

19. In a machine of the class described, fastening inserting mechanism, a work support, shaping means for the work comprising members mounted between the work support and the inserting mechanism, and means for 40 moving the shaping members relatively to the work support to clamp the work thereon and relatively to each other to shape the work prior to the insertion of the fastening.

20. In a machine of the class described, a 45 work support, shaping means for the work comprising shaping members one of which is mounted on the frame of the machine, a slide reciprocably mounted on the work support, a co-operating shaping member pivotally mounted on said slide, means for limiting the pivotal movement of said shaping member, and means for causing reciprocation of said slide to cause the co-operation of said shaping members.

21. In a machine of the class described, 55 fastening inserting mechanism, a work support, shaping means for the work comprising a shaping member mounted on the frame of the machine and adjustable toward and from the co-operating shaping member, a co-operating shaping member mounted on the work support, and a cam for controlling the movements of the last-mentioned shaping member, said cam being adjustable to 60 permit adjustment of the last-mentioned

shaping member so that both shaping members can be adjusted relatively to the inserting mechanism.

22. In a machine of the class described, a work support having a work supporting 70 surface, shaping members for the work mounted above the work support and movable toward and from each other in a plane parallel to said surface, and means comprising a stationary cam for causing the co-operation of said shaping members in said plane, said cam having a cam surface for causing approaching movement of the shaping members and a second cam surface for completing the approaching movement and for retaining the shaping members in clamped relation to the work. 75 80

23. In a machine of the class described designed to apply a reinforce to a sole, a work support, a shaping member constructed 85 and arranged to be heated to the desired degree, a co-operating shaping member mounted on the work support, the said shaping members being so mounted as to adjust themselves automatically to each other and to the 90 work in shaping the work and applying the reinforce, and means for inserting a fastening into the work after the shaping operation.

24. In a machine of the class described, 95 shaping means for the work comprising a V-shaped member and a co-operating shaping member having a correspondingly V-shaped notch, the shaping members having surfaces to engage opposite surfaces on a piece of 100 work to compress the portion of work engaged between the shaping members, and means for inserting a fastening to secure the work in its shaped condition.

25. In a machine for shaping the toe portion of the lip of an insole, in combination, 105 a member to engage the inner side of the lip at its toe portion, a co-operating member to engage the lip on its outer surface and movable toward and from the member within the 110 lip, means for moving said co-operating member toward the other member, and an actuating device for said means co-operating with the first mentioned member to cause engagement of the latter with the insole. 115

26. In a machine for shaping the toe portion of the lip of an insole, in combination, 120 a shaping member to engage the inner surface of the lip at its toe portion and movable in a substantially vertical path, a co-operating shaping member to engage the outside of the lip at its toe portion and movable in a substantially horizontal path toward and from said inner shaping member; and a lever operatively connected with both of said 125 shaping members to cause engagement of the shaping members with the work.

27. In a machine for shaping the toe portion of the lip of an insole, in combination, 130 a shaping member to engage the inner sur-

face of the lip at its toe portion and movable in a substantially vertical path, a co-operating shaping member to engage the outside of the lip at its toe portion and movable in a substantially horizontal path toward and from said inner shaping member, and a single lever for causing the operation of both of said shaping members.

28. In a machine for shaping the toe portion of the lip of an insole, in combination, 10 a frame, a work-plate, a wedge-shaped block slidably mounted in said frame and arranged to operate upon the inner side of the lip at its toe portion, a forming member co-operat-

ing with said block and having diverging jaws movable with relation to said wedge-shaped block to engage the lip on its outer surface, means for moving said forming member, and a lever for causing relative movement between said block and work- 20 plate to clamp the insole, said lever being also operative in co-operation with said moving means to cause the forming member to move toward the wedge-shaped block.

In testimony whereof I have signed my 25 name to this specification.

FRED N. LA CHAPELLE.
